UNITED STATES PATENT OFFICE

GEORGE N. TOWERS, OF ROY, WASHINGTON

PAPER HANDLING DEVICE

Application filed April 30, 1930. Serial No. 448,527.

This invention relates generally to the wrapping of packages, and particularly to devices for holding wrapping paper.

The main object of this invention is to provide an exceedingly simple and efficient form of paper handling mechanism whereby the paper may be supported beneath the table or wrapping counter in roll form and drawn up through a slit in the table, the sides of which 10 slit are yieldable to give access to the end of the paper on the roll after a piece has been torn therefrom.

The second object is to provide a form of paper holding mechanism which will be 15 simple in the extreme and which can be manufactured at a cost well within the range of even the small shop keeper.

These, and other objects, will become more apparent from the specification following as 20 illustrated in the accompanying drawings, in which:

Figure 1 is a transverse section through the counter and paper handling mechanism but not cutting through the paper roll.

25 Figure 2 is a fragmentary view similar to Fig. 1 showing the yieldable tearing edges depressed preparatory to tearing out the paper.

Figure 3 is a perspective view of one end 30 of the device showing a piece of paper being torn from the roll.

Similar numbers of reference refer to similar parts throughout the several views.

Referring in detail to the drawings, there 35 is shown the ordinary form of wrapping table 10 whose edges are supported by the apron 11 which is secured to the upright legs 12. In the table top 10 is formed a slot 13 into which downwardly extends a pair of standards 14 whose upper ends are secured to the ends of the slots 13 by means of the screws 15. Across the lower ends of the standards 14 is mounted a roll of paper 16 whose arbor 17 rests in suitable notches 18 40 formed in a block 19 secured on the inner sides of each of the standards 14. Between the upper ends of the standards 14 are hinged the trap doors 20 and 21 which are provided with the downturned ears 22. Rivets 23 pass 45 through the ears 22 and the standards 14. 50

The trap door 20 is provided with a short curved inner side 24 and the trap door 21 is provided with a longer curved side 25. The trap doors 20 and 21 are provided with springs 26 which urge them toward a closed position, as shown in Fig. 1. The adjacent edges 27 of the trap doors 20 and 21 may project slightly beyond the curved surfaces of the sides 24 and 25 for the purpose of forming tearing edges. In some instances these 55 may be serrated if desired.

Below the trap door 20 is placed an upright board 28 and below the trap door 21 is placed a cross member 29 having a sloping face 30 on which rides a roller 31 which may consist of one elongated member or a number of shorter ones, or even spheres such as marbles or rubber balls, the function being merely to wedge between the face 30 and the face 32 of the member 28 for the purpose of preventing the paper 33 from slipping downwardly after it is torn off and at the same time afford no hindrance to the withdrawal of the paper when desired.

Obviously, any other form of holding mechanism could be substituted for the member 31 without departing from the spirit of this invention.

The operation of the device is as follows: Assuming that the roll 16 has been placed in position and the paper 33 threaded upwardly, as shown in Fig. 1, until it passes between the adjacent edges 27 of the trap doors 20 and 21. If it is desired to obtain a piece of paper of any required length from the roll 16 it is only necessary to press the trap doors 20 and 21 downwardly, as shown in Fig. 2, which exposes the end of the paper 33 to the grasp of both of the hands 34.

It will be noted in this figure that the member 31 is not now in a wedging position but has been lifted away from same by the tension on the paper 33. As soon as the paper is withdrawn the desired length, the trap doors 20 and 21 are liberated allowing them to return to their horizontal position and the paper can be torn off after the fashion shown in Fig. 3.

It will be seen that by this device all feed rollers, ratchet mechanisms and other feed-

ing devices ordinarily required to provide a pulling edge for the paper are dispensed with. It must be understood that the trap doors 20 and 21 may extend over a portion or all of the width of the roll 16. There is a natural advantage, however, in making it the full width as it eliminates corners in the tearing edge and allows the operator to grasp the paper at any desired position with one or both hands.

10 I am aware of course that paper handling devices have been constructed in a great variety of forms; I therefore do not intend to cover such devices broadly but I do intend to cover all such forms and modifications thereof as fall fairly within the appended claims.

I claim:

1. In a paper handling device the combination of a wrapping surface having a longitudinal opening formed therein, a pair of trap doors forming a closure for said opening arranged to be depressed along the longitudinal center line of said opening, an upright holding board mounted along said longitudinal center line underneath the union of said trap doors, an inclined member adjacent to said holding board, and a paper holding member having a circular cross section lying between said inclined surface and said upright holding member.

2. A paper handling machine consisting of a pair of upright standards, means for supporting a roll of paper between the lower ends thereof, an upright holding member past which said paper may be fed, an inclined member adjacent to said holding member and spaced therefrom through which space paper from said roll may be fed, and a circular member riding on said inclined member adapted to hold said paper against said upright member.

GEORGE N. TOWERS.
